US0D1102930S

(12) **United States Design Patent** (10) Patent No.: **US D1,102,930 S**
(45) Date of Patent: ** Nov. 25, 2025

(54) **WATCH DIAL**

(71) Applicant: **Omega SA**, Biel/Bienne (CH)
(72) Inventor: **Gregory Kissling**, Biel/Bienne (CH)
(73) Assignee: **Omega SA**, Biel/Bienne (CH)

(**) Term: **15 Years**

(21) Appl. No.: **29/921,322**

(22) Filed: **Dec. 15, 2023**

(30) **Foreign Application Priority Data**

Jun. 20, 2023 (WO) WIPO134522
(51) **LOC (15) Cl.** **10-07**
(52) **U.S. Cl.**
USPC **D10/126**
